CENTRIFUGE

Alfred E. Drissner and Gustav B. Petsche, Cleveland, Ohio, assignors to The National Acme Company, Cleveland, Ohio, a Corporation of Ohio

Application October 15, 1930. Serial No. 488,802

3 Claims. (Cl. 233—34)

This invention relates to centrifuges, the object of the invention being to provide an improved centrifuge wherein the capacity of the same will be increased, and to do this in a simple and efficient manner, the present invention being an improvement upon that shown and described in Letters Patent No. 1,714,986, dated May 28, 1929, granted to Paterson and Petsche, and reference to which patent is made for the detailed description of the construction of the centrifuge which is herein deemed unnecessary since the construction of the major parts of the centrifuge shown herein may be similar to that disclosed in that patent.

15 In the drawings accompanying and forming a part of this specification, Figure 1 is a vertical section of this improved centrifuge.

Figure 2 is an enlarged detail view of the lower end of the bowl.

20 Figure 3 is a bottom view of the bowl.

Figure 4 is a view of the lower portion of the impeller blade.

Figure 5 is a top view of the impeller blade, and

25 Figure 6 is a partly sectional edge view thereof.

Similar characters of reference indicate corresponding parts in the several views.

Before explaining in detail the present improvement and mode of operation thereof, we desire to have it understood that the invention is not limited to the details of construction and arrangement of parts which are illustrated in the accompanying drawings, since the invention 35 is capable of other embodiments, and that the phraseology employed is for the purpose of description and not of limitation.

The centrifuge shown and described comprises a suitable bowl 2 located within a housing, not 40 shown, and rotated by a suitable means and provided with a bottom or base plate 3 and an upper disk or closure 4, and within this bowl is usually located a plurality of cylinders or tubes including a central tube 5 supported by a disk 6 having suitable radial ports 7 communicating with the bowl.

The tube 5 extends upwardly through the bowl and at the top thereof is located a plurality of receptacles or pans for the reception of the 45 separated or clarified fluids. Opening into the top of the tube 5 is a jet nozzle or inlet tube 8 for the passage of the fluid to be treated. Located within this inner tube is a twisted or screw-formed paddle or impeller blade 9 having its upper end close to and almost touching the

mouth of the inlet tube whereby the jet of fluid from the inlet tube is shot onto the end of the impeller with some force and thus not given an opportunity to disperse and lose its energy in the wrong direction as would be the case where 60 the upper end of the impeller located away from the inlet tube, being suitably secured in position at its lower end to the disk 6 for rotation with the bowl and having a diameter substantially coincident with the interior diameter of 65 the tube, and in the present instance, the blade is provided with a pair of radial ears or off-set portions 10 adapted to be engaged by a pair of pins 11 carried at the under side of the disk 6, the disk having a central opening therethrough 70 for the passage of the blade, whereby, as the bowl and the disk 6 are rotated, these pins engage the ears of the projections 10 of the impeller blade and likewise rotate it.

In the present instance, the blade is shown as 75 made of sheet metal reinforced at its lower end by a pair of overlapping members 12 suitably riveted or secured to the twisted blade portion and which is shown provided with an opening 13 through the reinforced portions of the blade. 80

By reason of this twisted or screw-formed impeller blade located in the intake tube of the centrifuge, the capacity of the machine is materially increased, tests having demonstrated that this impeller blade increases the capacity 85 of the machine from fifteen gallons per minute to sixty gallons per minute, in that it causes the fluid to be fed through faster, thereby increasing the capacity of the machine.

From the foregoing it will be seen that by 90 twisting the impeller blade laterally extending wings are formed to assist in facilitating the passage of the fluid by reason of the fact that it speeds it up during its passage through the intake tube and which speeding up is, of course, in a rotary direction. Obviously this twisted impeller blade could have wings secured thereto in any suitable way, either formed as a part thereof or as by casting or riveting or otherwise shaping the impeller blade. 95

It is to be understood that, by describing in detail herein any particular form, structure or arrangement, it is not intended to limit the invention beyond the terms of the several claims 105 or the requirements of the prior art.

Having thus explained the nature of our said invention and described a way of constructing and using the same, although without attempting to set forth all of the forms in which it may 110

be made, or all of the modes of its use, we claim:

1. In a machine of the class described, the combination of a non-slidable rotary bowl, a disk secured thereto at the bottom thereof, an intake tube located within said bowl for rotation therewith, an inlet tube communicating with the top of said first tube, and a twisted impeller blade secured only at the lower end thereof to said disk and having its upper end adjacent to the inlet tube, said impeller blade extending through the disk.

2. In a machine of the class described, the combination of a non-slidable rotary bowl constructed to discharge all its contents simultaneously during the rotation thereof, a disk secured thereto at the bottom thereof, an intake tube located within said bowl for rotation therewith, an inlet tube communicating with the top of said first tube, and a twisted impeller blade secured at the lower end thereof to said disk and

having its upper end adjacent to the inlet tube, said impeller blade extending through the disk and having a pair of radially extending ears co-operating with a pair of pins carried at the bottom of the disk for rotating the impeller blade.

80

3. In a machine of the class described, the combination of a rotary bowl, an intake tube therein extending to the bottom of the bowl, a jet producing nozzle within said intake tube and located above the top of the bowl, a rotary impeller having a long gradual twist and with a single pitch extending from end to end thereby to act as a paddle supported at the bottom of the bowl and terminating adjacent to said nozzle and above the top of the bowl, and constructed to impart a rapid rotary movement to the fluid from said nozzle.
